UNITED STATES PATENT OFFICE.

ISAAC STEINAU, OF NEW YORK, N. Y.

DESIGN FOR A DISPLAY-STAND.

SPECIFICATION forming part of Design No. 33,802, dated December 25, 1900.

Application filed November 26, 1900. Serial No. 37,837. Term of patent 3½ years.

To all whom it may concern:

Be it known that I, ISAAC STEINAU, a citizen of the United States, and a resident of the city of New York, borough of Manhattan, 5 in the county and State of New York, have invented and produced a new and original Design for a Display-Stand, of which the following is a full, clear, and exact description.

Reference is to be had to the accompanying drawings, forming a part of this specification, in which similar characters of reference indicate corresponding parts in both the views.

Figure 1 is a perspective view of a display-stand, showing my design; and Fig. 2 is a 5 sectional side elevation of the same.

The design in its entirety consists of the circular base A, from which rises a rim B, simulating a shirt-collar, radially arranged

partitions C extending inwardly from the inside of the said rim to a center piece D, on 20 which appears a handle E in the form of a collar-button.

The leading feature of the design consists of a rim simulating a shirt-collar.

Having thus fully described my invention, 25 I claim as new and desire to secure by Letters Patent—

The design for a display-stand, herein shown and described.

In testimony whereof I have signed my 30 name to this specification in the presence of two subscribing witnesses.

ISAAC STEINAU.
